UNITED STATES PATENT OFFICE.

HENRY A. CARPENTER, OF SEWICKLEY, PENNSYLVANIA, ASSIGNOR TO RITER-CONLEY MANUFACTURING COMPANY, OF PITTSBURGH, PENNSYLVANIA, A CORPORATION OF NEW JERSEY.

COAL-GAS-GENERATING APPARATUS.

1,140,797.

Specification of Letters Patent.

Patented May 25, 1915.

Application filed September 14, 1914. Serial No. 861,493.

To all whom it may concern:

Be it known that I, HENRY A. CARPENTER, a citizen of the United States, and a resident of Sewickley, in the county of Allegheny and State of Pennsylvania, have invented certain new and useful Improvements in Coal-Gas-Generating Apparatus, of which the following is a specification.

A serious difficulty in the operation of coal gas generating apparatus is the tendency of solids carried forward by the gas or which form therein by condensation to deposit on the walls of the offtake passages and so clog and obstruct the same as to greatly retard the operation unless the passages are frequently cleaned. In apparatus of prior design the gas is conducted from the retort to the stand-pipe through a connecting conduit or passageway of appreciable length which affords ready lodgment for the obstructing solids.

The primary object of this invention is to so construct and assemble the retorts or their mouth-pieces and the stand-pipe as to eliminate a connecting conduit of appreciable length by arranging said parts in abutting relation. The axial length or extent of the communicating opening is still further reduced by eliminating one of the abutting walls, so that the abutting portions of the closely adjacent parts are separated only by a single wall through which the communicating port is formed. In the present adaptation the adjacent side of the retort mouth-piece is open and is adapted to fit against and be closed by an upright wall of the stand-pipe, the latter being provided with the port through which communication is maintained. Thus, while an efficient gas passage is provided, a conduit or passageway of appreciable length is avoided. In those forms of apparatus in which a stand-pipe is common to two upright rows or series of retorts, the pipe is simply fitted between the adjacent sides of the rows of mouth-pieces, closing the open faces of the latter and providing the direct ported outlet therefor without the intervention of connecting conduits.

50 A further purpose is to provide valve means of improved construction for controlling communication between the retorts and stand-pipe.

In the accompanying drawings, Figure 1 is a sectional plan of a portion of a gas bench equipped with the invention, the retort at the left hand of the view being shown in top plan, and the retort at the right hand in sectional plan, the adjacent portions of the right hand retort and the stand-pipe being shown on the irregular line 1-1 of Fig. 3. Fig. 2 is a view partly in front elevation and partly in section of retorts and a portion of the length of a stand-pipe constructed in accordance with the invention. Fig. 3 is a vertical longitudinal section of a portion of a stand-pipe taken on the line 3-3 of Fig. 1.

Referring to the drawings, the retorts 2 are set in a bench in the usual manner, and constituting an extension or continuation of each retort is a mouth-piece 3, the open outer end of which is closed by door 4 in the usual manner. The opposite side walls of the mouth-piece are equally spaced from the longitudinal center of the mouth-piece, there being no lateral neck-like offset for connecting with the stand-pipe such as has been usually provided heretofore.

In order to eliminate the conduit or passageway of appreciable length heretofore interposed between the retort or mouth-piece and the stand-pipe 5, an upright wall of the latter is caused to abut one side of the mouth-piece. To minimize as far as possible the thickness of material between the mouth-piece and stand-pipe, an abutting wall of one of the parts is eliminated so that they are separated only by the thickness of the wall of the other part. In the present adaptation this is accomplished by forming the abutting face of the mouth-piece open with the stand-pipe fitting and closing the same. A structurally desirable arrangement is to form the outer end of the mouth-piece 95 with flange 6 and its inner end with flange 7, with the space between the flanges of just sufficient width to receive the stand-pipe and with the flanges secured to the latter, thereby firmly uniting the parts. Also, the top 100 and bottom of the mouth-piece may be flanged at 8 for securing to the stand-pipe as shown. When two rows or tiers of retorts are connected to the same stand-pipe, the latter is simply fitted therebetween as shown 105 in the drawings, eliminating the objection-

able lateral conduits by providing direct connection between the stand-pipe and each retort through a port 9 formed in the stand-pipe wall.

- 5 When communication between the retort and stand-pipe is valve controlled, the valve 10 for each port 9 is of disk form and slideable on the inner surface of the stand-pipe, said surface providing an efficient seat, and 10 the sliding of the valve and its pressure against the seat maintains a gas-tight fit. Pressure of the valve toward its seat is afforded by the valve-carrying spring arm 11 which is secured to the inner end of shaft 12, the latter extending through the wall of 15 the stand-pipe beneath the retort and parallel with the axis of port 9. The shaft is rotatable in the housing 13 secured to the stand-pipe, with a spring 14 confined in the 20 housing behind the handle-carrying head 15 of the shaft for exerting pressure in a direction to hold valve 10 tightly on its seat. Thus it will be seen that spring 14 and spring arm 11 coöperate in maintaining 25 the seat-cleaning and gas-sealing functions of the valve. The angular bracket-like portion 16 of housing 13 serves to close slot or passage 17 in a corner of the stand-pipe through which valve 10 and its supporting 30 and operating arm 11 are entered and removed without detaching them from the housing. Hence, to repair or replace the valve it is only necessary to remove the housing-securing bolts 18 and so turn or 35 cant the housing as to pass the arm and valve through the slot.

I claim:—

1. In gas generating apparatus, a horizontal retort, and a stand-pipe at one side 40 of the retort and extending above and below the same with a vertical wall of the pipe abutting against one side of the retort and in ported communication therewith.

2. In gas generating apparatus, a horizontal retort having an open side wall, and a stand-pipe at one side of the retort and extending above and below the same with a vertical wall of the pipe abutting against and closing the open side wall of the retort, 50 said side wall having a port for establishing communication between the retort and stand-pipe.

3. In gas generating apparatus, a plurality of horizontal retorts arranged one 55 above the other, and a stand-pipe at one side of and extending above and below the retorts and in abutting relation therewith, the abutting portions of the stand-pipe and retorts being ported to place each retort in direct communication with the stand-pipe.

4. In gas generating apparatus, a horizontal retort and retort mouth-piece, and a

stand-pipe at one side of the mouth-piece with a vertical wall of the pipe abutting against one side of the mouth-piece and in 65 ported communication therewith, the mouth-piece flanged to overlap the stand-pipe with the flanged portion secured thereto.

5. In gas generating apparatus, a horizontal retort and retort mouth-piece, a 70 stand-pipe at one side of the mouth-piece with a vertical wall of the pipe abutting against one side of the mouth-piece and in ported communication therewith, and flanges projecting from the pipe-abutting 75 side of the mouth-piece with the flanges overlapping and secured respectively to the front and rear walls of the stand-pipe.

6. In gas generating apparatus, a retort mouth-piece and a stand-pipe arranged side 80 by side with a wall common to and separating the adjacent sides of the mouth-piece and stand-pipe, said wall having a port for establishing communication between the mouth-piece and stand-pipe, and a valve for 85 said port.

7. In gas generating apparatus, a retort and a stand-pipe arranged in abutting relation with the wall of the abutting portion of one of said parts removed and with the 90 abutting wall of the other part separating said parts, said wall provided with a port through which the parts communicate.

8. In gas generating apparatus, a stand-pipe, and a retort mouth-piece having an 95 open side with said open side fitting and closed by a vertical wall of the stand-pipe, the stand-pipe wall formed with a port for establishing communication with the mouth-piece.

9. In gas generating apparatus, a retort mouth-piece having a wall forming a continuation of a corresponding retort wall and with the said mouth-piece wall open, and a stand-pipe at one side of the mouth-piece 105 with a vertical wall of the stand pipe fitting and closing the open mouth-piece wall, the stand-pipe wall having a port for establishing communication with the mouth-piece.

10. In gas generating apparatus, a retort 110 mouth-piece having an open side with lateral extensions on the mouth-piece adjacent to the opening, and a stand-pipe fitting between and secured to said extensions with a vertical wall of the pipe closing the open 115 side of the mouth-piece, the stand-pipe wall having a port for establishing communication with the mouth-piece.

In testimony whereof I affix my signature in presence of two witnesses:
